DUST SCRAPER FOR ELEVATING GRADERS

Filed Dec. 9, 1927

Inventor
F.H.Lundean,

By *Clarence A. O'Brien*
Attorney

UNITED STATES PATENT OFFICE.

FRED H. LUNDEAN, OF BUCKLIN, MISSOURI.

DUST SCRAPER FOR ELEVATING GRADERS.

Application filed December 9, 1927. Serial No. 238,908.

The present invention relates to belt elevators, and more particularly to means for removing accumulation of dirt or other material from the inner face of the belt adjacent to its lower end where such material interferes with the operation of the conveyor by engagement between the belt and the operating roller or pulley.

An important object of the invention resides in the provision of such a device which may be attached to belt conveyors of the usual type, and having means for manually operating the device when desired.

A still further important object resides in the provision of a device of this nature which is simple in its construction, inexpensive to manufacture, and thoroughly efficient and reliable in operation.

A particular object of the invention is to provide such a cleanable belt conveyor of road grading machines.

Other objects and advantages will be apparent from the following description and it will be understood that changes in the specific structure shown and described may be made within the scope of the claims without departing from the spirit of the invention.

In the drawings forming a portion of this specification, and in which like numerals of reference indicate similar parts of the several views.

Figure 1 is a fragmentary longitudinal section through a road grader with an elevator mounted therein and showing parts of my device.

Figure 2 is a fragmentary longitudinal section through the lower end of the elevator showing associated parts of my device.

Figure 3 is a sectional view taken substantially on the line 3—3 of Figure 2, and

Figure 4 is a perspective view of a guide bracket.

Referring to the drawing in detail, it will be seen that the numeral 5 denotes a portion of the frame of a road grader in which is supported an endless elevating mechanism 6 which comprises among other usual elements, side members *a*, a lower roller *b*, and an endless belt *c*. The sides *a* are provided with openings *d*. I place a pan 8 across the belt *c* between the runs thereof adjacent the bottom roller *b*, this pan extending through the openings *d*. The pan 8 is formed with side flanges 9 extending in a plan transverse to the movement of the belt rising therefrom at

right angles and terminating at their upper edges inwardly directed extensions 10. The pan is open at its ends to permit ejection of the soil and is substantially rectangular in configuration. A scraper 11 is movable along the upper surface of the pan 8 and its ends are guided by the flanges 9 in their extensions 10. A rod 12 is pivotally engaged with the scraper as at 13 and is pivotally engaged as at 14 with a lever 15. The lever 15 extends through an opening 16 in a board 17 supported on the frame 5. The lever, intermediate its ends, is formed with a stop 18 which is too large to pass through the opening 16 and therefore will rest on the board 17 as is clearly shown in Figure 1. It will be seen, however, that the lever 15 may move upwardly if the endless elevator 6 is moved upwardly as happens in certain classes of road graders. The numeral 19 denotes an axle at the rear of the road grader and I mount thereon a U-shaped guide bracket *G* one leg of which is longer than the other terminating in a plate 20 secured to the top of the axle 19 so that the guide bracket *G* extends rearwardly with its two legs in the same horizontal plane. The other leg is provided with a laterally outwardly extending projection 21. The lever 15 extends between the legs of the bracket *G*.

From the above detailed description it will be seen that every once in a while the operator of the machine may actuate the lever 15 so as to move the scraper 11 back and forth along the pan 8 so as to eject any dirt or the like which may have collected thereon. This will prevent the conveyor from becoming out of order as happens quite frequently under the usual present practice because this shows dirt and the like that is on the inside of the belt and between the belt and the rollers thereby causing considerable resistance in the case of big clogs of dirt or stones makes the elevator inoperative.

It will also be seen that the structure is very easy to install in an inexpensive yet strong and durable manner.

The present embodiment of the invention has been disclosed in detail merely by way of example since in actual practice it attains the features of advantage enumerated as desirable in the statement of the invention and the above description. It will be apparent that changes in the details of construction, and in the combination and arrangement of parts may be resorted to without departing

from the spirit or scope of the invention as hereinafter claimed or sacrificing any of its advantages.

Having thus described my invention, what I claim as new is:

- 5 1. A cleaner for belt conveyors comprising a pan of substantially rectangular configuration adapted to be mounted between the runs of the belt and having a pair of opposed side flanges rising therefrom at right angles and terminating in inwardly directed extensions, a scraper movable along said pan having its ends guided by the flanges and their extensions, and means for moving the scraper.
- 10 2. A cleaner for belt conveyors comprising a pan of substantially rectangular configuration adapted to be mounted between the runs of the belt and having a pair of opposed side flanges rising therefrom at right angles and terminating in inwardly directed extensions, a scraper movable along said pan having its ends guided by the flanges and their extensions, a rod pivotally engaged with the scraper, a lever pivotally engaged with the rod, a
- 15 20 board having an opening through which the

lever projects, and a stop on the lever intermediate its ends larger than the opening to rest on top of the board.

3. A cleaner for belt conveyors comprising a pan of substantially rectangular configuration adapted to be mounted between the runs of the belt and having a pair of opposed side flanges rising therefrom at right angles and terminating in inwardly directed extensions, a scraper movable along said pan having its ends guided by the flanges and their extensions, a rod pivotally engaged with the scraper, a lever pivotally engaged with the rod, a board having an opening through which the lever projects, a stop on the lever intermediate its ends larger than the opening to rest on top of the board, an elongated guide bracket of U-shaped formation having one blade longer than the other, the terminal of the longer leg being adapted to be fixed to the axle of a machine, and the lever projecting between the legs of the bracket.

In testimony whereof I affix my signature,

FRED H. LUNDEAN.
